United States Patent Office

Des. 221,457
Patented Aug. 17, 1971

221,457

TOY WHEELED VEHICLE

Richard E. Henderson, Huntington Beach, Calif., assignor
to Mattel, Inc., Hawthorne, Calif.

Filed June 8, 1970, Ser. No. 23,359

Term of patent 14 years

Int. Cl. D21—01

U.S. Cl. D34—15

FIG. 4

FIG. 5

FIG. 6

FIG. 1 is a front perspective view of a toy wheeled vehicle, showing my new design; and

FIG. 2 is a left side elevational view, the right side being a mirror image thereof; and

FIG. 3 is a front elevational view thereof; and

FIG. 4 is a top plan view thereof; and

FIG. 5 is a rear elevational view thereof; and

FIG. 6 is a bottom plan viewed thereof.

I claim:

The ornamental design for a toy wheeled vehicle, as shown and described.
